UNITED STATES PATENT OFFICE.

HENRY McCOBB, OF NEW YORK, N. Y.

CHOCOLATE-PACKAGE.

SPECIFICATION forming part of Letters Patent No. 268,511, dated December 5, 1882.

Application filed October 13, 1882. (Model.)

To all whom it may concern:

Be it known that I, HENRY McCOBB, of the city, county, and State of New York, have invented a certain new and useful Improvement 5 in Chocolate-Packages, of which the following is a full, clear, and exact description.

Reference is to be had to the accompanying drawings, forming part of this specification, in which similar letters of reference indicate 10 corresponding parts in both the figures.

Figure 1 is a sectional side elevation of my improvement. Fig. 2 is a perspective view of the cover of the package.

The object of this invention is to improve the 15 construction of the packages for which Letters Patent No. 259,887 were issued to me June 20, 1882, in such a manner as to make them neater in appearance and a better protection to their contents.

20 The invention consists in a box or package made with a removable cover, and having a grater secured at its side edges to the side flanges of the said cover, as will be hereinafter fully described.

25 A represents the body of the package, which can be made of decorated tin or other suitable material.

B is the cover of the package or box, which is made with flanged edges to fit upon the top 30 of the box A.

To the inner surface of the side flanges of the cover B are secured, by solder or other suitable means, the side edges of the grater C, which is formed of tin, punctured from the inner side or the side next the cover B, so that the burrs of the punctures or the grating-surface will be outward. The grater C is made 35 shorter than the cover B, so that a space will be left between each end of the grater C and 40 the end flange of the cover B, as shown in Figs. 1 and 2, to allow any of the chocolate or other substance being grated that may pass through the punctures of the grater to be readily removed.

45 With this construction the package or box, when closed, will have a much neater appear-

ance than when the punctures are formed through the body of the cover, as shown and described in Letters Patent No. 259,887.

With this construction, also, the grater is 50 protected from the dust and from contact with any substance except the one to be grated.

It will be noticed that the flanges of the cover B project beyond the burred surface of the grater C, so that when any substance is being grated the said flanges will form side guides and end stops for the substance, to guide and limit its movement, making the grater more convenient in use. The projecting flanges also serve to prevent the scattering and wasting of 60 the grated substance.

Having thus fully described my invention, I claim as new and desire to secure by Letters Patent—

1. A chocolate-package cover provided with 65 flanges to which the grater is appended, as and for the purpose specified.

2. In a box or package, the combination, 70 with the removable cover B of the body A, of a grater, C, made shorter than the said cover and attached at its side edges to the side flanges of the said cover, substantially as herein shown and described, whereby the grater will be kept from contact with extraneous substances, as set forth.

3. In a box or package, the combination, 75 with the cover B of the box A, of the grater C, whose burred surface is below the edges of the flanges of the cover, to provide side guides and end stops to guide and limit the movements of the substance being grated and prevent waste of the grated material, substantially as shown and described.

4. In a box or package, the grater C, arranged in the cover B, with its burred surface 80 below the edges of the flanges of the cover and made shorter than the cover, substantially as herein shown and described.

HENRY McCOBB.
